UNITED STATES PATENT OFFICE

2,550,135

DETACHABLE LOOP-TYPE KEY HOLDER
FOR KEY CASES

Thomas A. Buckley, Longmeadow, Mass., assignor to Buxton, Incorporated, Springfield, Mass., a corporation of Massachusetts

Application August 9, 1947, Serial No. 767,802

1 Claim. (Cl. 70—456)

1

This invention relates to a key holder of the closed loop type, adapted to be releasably connected to the key supporting structure of a key case.

The principal objects of my invention are to provide a key holder of the above type which is more economical to manufacture and one which will operate in a more efficient manner in the supporting structure of the key case.

Other and further objects residing in the details of the structure will be made apparent in the following specification and claim.

In the accompanying drawings:

Fig. 1 is an elevational view of a key holder embodying my invention;

Fig. 2 is an elevational view of the structure shown in Fig. 1, looking from the right in the latter figure;

Fig. 3 is a detail sectional view substantially on line 3—3 of Fig. 2;

Fig. 4 is a detail sectional view substantially on line 4—4 of Fig. 2;

Fig. 5 is a fragmentary view showing the loop connected to the supporting structure of a key case;

Fig. 6 is a detail sectional view similar to Fig. 3 but showing a modified structure;

Fig. 7 is a view similar to Fig. 6 but showing an alternative structure;

Fig. 8 is a transverse sectional view showing another alternative structure; and

Fig. 9 is a view showing the manner of introducing a key into the holder prior to the connection of the holder to the supporting structure of the key case.

The key holder is made from a single strip or piece of flat spring material. The end portions of the strip are each pressed, or otherwise shaped, to the form of a hollow hemisphere as at 1 and 2 and the central portion of the strip is bent to form a closed loop as at 3 and to bring the hemispheres into face to face relation, the contacting hemispheres forming a substantially spherical head as generally indicated at 4. The portions of the strip 5 and 6, intermediate the loop and the head-forming hemispheres, are bent into substantially parallel face to face relation to form a shank portion, as indicated at 7. The hemispheres and shank forming portions are normally held in closed, contacting relation by the spring action of the material of which the loop is formed.

In use a key is positioned on the loop and the head 4 is connected to the key support 8 of a key case 9, as shown in Fig. 5. The key support

2

5 may take any suitable form, that shown comprising a hollow generally cylindrical member 10 provided with a slot 11 having an enlarged opening 12 through which the head 4 of the holder is introduced into the cylinder, the shank 7 turning and swinging in the slot 11 to provide for the desired manipulative movement of the holder in the use of the key.

In the manipulative movements of the key, a twisting movement is frequently imposed on the sides of the loop which tend to displace the hemispheres in the plane of their contact, that is to cause one to slide past the other. Such displacement interferes with the desired freedom of movement of the head and shank in the support, and tends to cause undue wear of both the holder and support.

20 It has been proposed, as disclosed in the prior patent to Warner R. Buxton, No. 2,018,009, to prevent this sidewise displacement of the head forming members, by providing the engaging faces of the head forming members with interengaging projections and depressions. This has proved reasonably effective when the spring pressure, exerted by the material of the loop, which acts to hold the head forming members together is substantial. This has required a relatively heavy loop, formed of high quality spring steel, which has increased the material cost and the difficulty of shaping the head and loop. In many cases the quality of the steel used for this purpose has been higher than is needed for the proper functioning of the loops in all other respects.

35 I have found that the force of the spring action necessary to hold the head members in place and therefore the weight and spring quality of material of which the loop is formed may be reduced, and brought more into line with the other requirements of the structure, by locating the interlocking means in the shank portion and spacing it sufficiently from the head to position it outwardly of the supporting means of the key case. I have further found that by also spacing the locking means a proper distance from the entrance to the loop, a more positive locking means may be used without interfering with the insertion or removal of the key into or from the loop of the holder.

40 In the embodiment of my invention shown in Figs. 1, 2 and 3, a portion 13 of shank member 5 is pressed inwardly forming a projection which engages in a depression formed by pressing a 45 portion 14 of shank 6 outwardly, as best shown

50 portion 14 of shank 6 outwardly, as best shown

in Fig. 3. The portions 13 and 14 form inter-engaging portions which prevent relative movement of the cupped ends 1 and 2 in the plane of their contact.

In Fig. 6 the outwardly pressed member 14 is replaced by an opening 15 formed in shank member 6, in which the projection 13 engages. In Fig. 7 the projection 13 is replaced by a small tongue 16 bent inwardly from the material of shank 5 and engaging in opening 15 of shank member 6.

An alternative form of interlock is shown in Fig. 8 in which a portion of one of the shank members 6 is reduced in width as by cuts 17. The corresponding portion of the other shank member 5 is then crimped or bent inwardly into the cuts 17 forming small projections 18 which embrace the portions of shank member 6 between the cuts 17.

It will be seen that in all of the forms described the lock against sidewise movement of the head forming hemispherical members is positioned closely adjacent the loop portion of the holder where the twisting action tending to slide the head members originates. The forces tending to displace the shank members sidewise are thus not increased by the leverage advantage which is present when the lock is placed in the head as in prior construction. Moreover the spring force acting directly to hold the shank members together is greater near the loop than at the more remote head and the "depth" of interlock necessary to maintain the parts sidewise movement is less. As a result the spring action need be only sufficient to maintain the loop closed against usual movement of the keys on the loop. This makes possible a light and less expensive loop construction and greater ease in placing keys in, or removing them from the loop.

In placing the keys on the loop the handle portion 19 of the key is inserted in the loop as shown in dotted lines in Fig. 9. The key is then moved upwardly until the head members are on opposite sides of the opening 20 in the key when the latter is tipped over to thread one of the head and shank members through the opening in an obvious manner. The separation of the shank members and of the locking members carried thereby, in placing a key on the loop and in removing it therefrom, is effected by the wedging engagement of the outer or inner edge of the key handle in the loop exit indicated at 21. The shank lock is preferably spaced from the entrance only sufficiently to assure that the interlocking members are completely separated

from each other when the edge of the key reaches the lock. This spacing as well as the size and thickness of the parts have been exaggerated in the drawings for the sake of clearness. As is apparent in the drawings the projecting member of the lock in each case presents an inclined or curved surface to the advancing edge of the key as it enters or leaves the loop facilitating the passage of the key past the lock.

10 I claim:

A key holder of the closed loop-type having an enlarged head at the free ends of the loop by which the holder is releasably held within the supporting mechanism of a key case which comprises a strip of flat spring material having enlarged ends in the form of hollow substantially semi-spherical cups the intermediate portion of the strip being bent into the form of a loop with the open sides of the cupped ends held in contact with each other to normally form a substantially spherical head by the inherent spring of the material, the portions of the strip adjacent the cupped ends lying in flat face to face contact to form a shank portion intermediate said head and the loop, one portion of the strip forming the shank being formed with a projection and the other shank forming portion being formed with a recess to receive the projection to prevent relative movement of the cupped ends in the plane of their contact, said projection and recess being confined to a portion of the shank spaced from both the cupped ends and the exit from the loop, whereby the entrance to the loop will be positioned within the supporting mechanism while the said projection and recess will be positioned outwardly of said mechanism, the side of the projection toward the loop being inclined in the direction of the head.

THOMAS A. BUCKLEY.
